UNITED STATES PATENT OFFICE.

THOMAS P. ARCHER AND ERNEST E. HEINTZ, OF DETROIT, MICHIGAN, ASSIGNEES TO
TERNSTEDT MANUFACTURING COMPANY, OF DETROIT, MICHIGAN, A CORPORA-
TION OF MICHIGAN.

DOOR LOCK.

Application filed June 16, 1924. Serial No. 720,224.

To all whom it may concern:

Be it known that we, THOMAS P. ARCHER and ERNEST E. HEINTZ, citizens of the United States, residing at Detroit, in the county of Wayne and State of Michigan, have invented certain new and useful Improvements in Door Locks, of which the following is a specification.

This invention relates to a lock, and is more particularly directed to the dogging mechanism and the control thereof.

The object is to provide a simple and positive actuating means for controlling the dogging mechanism. A further object is to provide means whereby the dogging control may be carried by a stamping which is detachably secured to the lock casing over the trimming. This enables the manufacturer to assemble this control after the job has been completed and the trimming secured in place.

One of the difficulties with dog controls of the present art is that they are relatively expensive to manufacture and are not easily assembled in the lock casing. In a prior application, Serial No. 522,211, there is shown a dogging control which is much more expensive to build and is not so easily assembled in the casing. We have provided a snap-over control that is cheaply constructed, easily assembled and is positively actuating to throw the same completely "on" or completely "off", there being no chance of the snap-over remaining in an intermediate position, as the snap-over button is yieldably forced into either the "off" or "on" position.

In the drawings:

Fig. 1 is an elevation of a lock constructed in accordance with our invention with the back-plate removed.

Fig. 2 is an elevation of the front of the lock showing the snap-over escutcheon.

Fig. 3 is a section through the snap-over control taken on the line 3-3 of Fig. 2.

Fig. 4 is an elevational view similar to Fig. 1, showing the dog in an "off" position.

Fig. 5 is a horizontal sectional view taken on the line 5-5 of Fig. 4.

50 The lock construction embodies elements which are mostly old in the prior art.

~~a~~ designates a vertical rotary spindle provided with an offset portion *b*, which is adapted to engage the ears *c* turned up

from the sliding bolt *d*. On rotation of the 55 spindle the bolt *d* is retracted within the casing in the usual manner. The spindle is supported in suitable bearings *e* secured to the front plate *f*. A coil spring *g* has its free end bearing against the end of the sliding bolt for yieldably projecting the bolt 60 from said casing. A coil spring *h* is suitably carried on the spindle for exerting a pressure for holding the vertical spindle against the ears carried by the sliding bolt 65 to prevent unnecessary rattle between the parts.

A yoke-shaped dog *i* is pivotally supported in the back-plate *j* as at *k*. A roll-back *m* operated by a handle outside of the car engages a projection *n* carried by a sliding bolt so that when the outside handle of the car is turned the bolt may be retracted. However, the roll-back is additionally provided with a shoulder *o*, which is engaged by 70 the dogging arm *p* which will prevent movement of the roll-back when the dog is in the position as shown in Fig. 1. The other arm of the dog designated *p'* is engaged in the cup-shaped member *q* actuated by the 75 tumbler lock. On the insertion of a key this dog may be actuated to release the roll-back so that one may retract the bolt for opening the door. This much of the construction is 80 old.

Our improvement resides in providing the dog with the tail *r*. The end of the tail *r* is provided with an opening *s* through which engages one end of the snap-over control 85 later to be described.

Secured to the lock casing by screws 10 is a snap-over escutcheon plate *t*. This escutcheon pivotally supports as at *u* a snap-over lever *v*. A small coil spring *w* is positioned about the lever between the tail *r* and the 90 back of the escutcheon plate. The normal tendency of this spring is to expand, and consequently it forces the lever to snap-over center one way or the other so that the spring 95 may expand as far as possible. In the position shown in Fig. 3 the lever is in the "on" position; that is, holding the dog in engagement with the shoulder of the roll-back for locking the same. As the snap-over lever 100 is pushed down by the finger, it is caused to pass center and the spring *w* then continuing the movement and forcing the snap-over lever to move the tail of the dog so as to 105

rock the yoke-like dog for disengaging the dog arm *p* from the shoulder *o* so as to release the lock.

In the operation of this dogging control 5 the snap-over may be snapped to the "on" position before one leaves the car; and the door closed from the outside. This locks the outside retractor. When the door is shut, it is only possible to release the dog by 10 inserting a key in the cylinder lock.

What we claim is:

1. In a lock, the combination of a lock casing, a sliding bolt, means for retracting the bolt, means for dogging the retracting means, and a finger-operated snap-over control for such dogging means automatically seeking either the extremity of the "off" or "on" position.

2. In a lock, the combination of a lock casing, a sliding bolt, means for retracting the bolt, means for dogging the retracting means, and a snap-over control for such dogging means positioned at a point remote from the said dogging means and automatically seeking either the extremity of the "off" or "on" position.

3. In a lock, the combination of a lock casing, a sliding bolt, means for retracting the bolt, a dog for dogging the retracting means and provided with a tail, and a lever snap-over center control for engaging said tail to actuate said dogging means.

4. In a lock, the combination of a lock casing, a sliding bolt, means for retracting the

bolt, means for dogging the retracting means, and a spring actuated lever snap-over control for such dogging means.

5. In a lock, the combination of a lock casing, a sliding bolt, means for retracting the bolt, means for dogging the retracting means, an escutcheon plate provided with means for controlling said dogging means, and means for detachably securing said escutcheon to the lock casing over the trimming.

6. In a lock, the combination of a lock casing, a sliding bolt, means for retracting the bolt, means for dogging the retracting means, an escutcheon plate formed of a stamping, a snap-over center control for said dogging means supported on the escutcheon, and means for detachably securing said escutcheon stamping to the lock casing over the trimming.

7. In a lock, the combination of a lock casing, a sliding bolt, means for retracting the bolt, means for dogging the retracting means, an escutcheon plate, a snap-over center control supported thereon for controlling said dogging means, fastening devices for detachably securing the escutcheon to the lock casing over the trimming, and means for spacing said escutcheon from the lock casing.

In testimony whereof we have affixed our signatures.

THOMAS P. ARCHER.
ERNEST E. HEINTZ.
